FIREARM

Eugene G. Reising, Hartford, Conn.

Application April 26, 1938, Serial No. 204,323

3 Claims. (CL 42-3)

My invention relates to that class of firearms that are commonly supported against the shoulder when being fired, and an object of my invention, among others, is the production of a firearm of this type having simple and efficient means for supplying ammunition to the barrel and for the regulation of such supply; and a further object of my invention is to provide a firing mechanism that is simple in construction and particularly efficient in operation.

One form of a firearm embodying my invention and in the construction and use of which the objects herein set out, as well as others, may be attained is illustrated in the accompanying drawings in which—

Figure 1 is a side view of my improved firearm.

Figure 2 is a view on enlarged scale in central lengthwise section through the stock of my improved firearm with the front portion broken off but showing the receiver and the rear end of the barrel.

Figure 3 is a similar view on a scale still further enlarged but showing the rear end of the stock only.

Figure 4 (Sheet 2) is a view on enlarged scale in central lengthwise section through a portion of the stock and mechanism supported thereby, the latter being shown ready for firing, the breach bolt and firing pin being in their forward positions and the hammer being cocked.

Figure 5 is a similar view but with the breach bolt, firing pin and hammer in their rearward positions just previous to the loading operation.

Figure 6 (Sheet 1) is a view in lengthwise section through a fragment of the stock showing the position of the sear and appurtenant parts just after its release of the hammer in a firing action.

Figure 7 is a similar view illustrating the operation of the hammer upon the sear during its forward movement.

Figure 8 is an isometric perspective view of the retainer for temporarily restraining movement of the cartridges in the magazine.

Figure 9 is a similar view of the discharge tip of the magazine.

Figure 10 (Sheet 2) is a view in cross section on a plane denoted by the dotted line 10—10 of Fig. 4.

Figure 11 is a similar view on a plane denoted by the dotted line 11—11 of Fig. 4.

Figure 12 is a similar view on a plane denoted by the dotted line 12—12 of Fig. 4.

Figure 13 is another similar view on a plane denoted by the dotted line 13—13 of Fig. 5.

Figure 14 is still another similar view on a

plane denoted by the dotted line 14—14 of Fig. 5.

In the accompanying drawings the numeral 15 denotes the stock of my improved firearm that may be composed of wood of any ordinary shape common to firearms of this type and which is recessed on its upper side to contain a receiver 16 to which the rear end of the barrel 17 is secured in any ordinary manner. The receiver is secured at its front end to the stock by means of a post 18 having a reduced threaded end screwed into the receiver the post being located in a recess in the stock, as shown in Fig. 4. A holding screw 19 extends through a bushing in the stock and into the post 18 to secure the latter and the receiver in place, this holding screw being knurled so that it may be turned by the thumb and fingers. A lug 20 projects from the inner end of the screw into the barrel 17 to support the latter.

A magazine 21 in the form of a tube extends 20 lengthwise through the stock, this tube being enclosed in a loading case 22 in the form of a tube that is threaded to receive a positioning nut 23 abutting against the inner end of a recess 24 extending inwardly from the butt of the stock 25 as shown in Fig. 3 of the drawings. A spring 25 thrusting at one end against a butt plate 26 and at its opposite end against the nut forces the case 22 into place in the stock. The magazine 21 projects out at the rear end of the case 22 30 and through the butt plate, and it is secured to the tube as by means of a bayonet lock 27 as shown in Fig. 3. The end of the magazine 21 is formed with a knurled fingerpiece 28 by means of which it may be turned in the case to unlock 35 it and permit its removal. The fingerpiece is located in a recess 29 in the butt plate. A loading spring 30 extends inwardly into the magazine and supports a plunger 31 at its front end, said plunger being forced against a line of cartridges 40 32 contained in the magazine.

The forward end of the magazine terminates in a discharge tip 33 permanently secured within the inner end of the magazine in any suitable manner as shown in Fig. 5 of the drawings.

A cartridge retainer or cut-off 35 is provided at one end with a lip 34 extending into a hole 36 in the magazine to hold the said cut-off from lengthwise movement, and at that end opposite the lip 34 with a fork 37 to fit over a cartridge 50 shell in front of the flange thereon, as shown in Fig. 5. A spring band 38 is formed on the retainer to partially encircle and tightly grasp the tip 33 to secure the retainer in place.

The receiver 16 is of generally cylindrical shape 55

with a bore of two diameters therethrough, the rear end of the bore being closed by a screw plug 39. A breech bolt 40 is fitted for sliding movement within the receiver, said bolt having a stop shoulder 41 to engage a similar shoulder on the inside of the receiver as shown in Fig. 4. A notch 42 is formed at the end of the breech bolt to receive a guide lug 43 projecting from the rear end of the barrel 17. A groove 44 is cut into the bottom of the breech bolt, extending lengthwise therein for the reception of a firing pin slide 45 having a firing pin 46 projecting from its end in position to strike a cartridge located in the firing chamber in the rear end of the barrel. A lug 47 extends laterally from the side of the firing pin slide to receive pressure of a firing pin spring 48 located in a bore 49 extending inwardly from the rear end of the breech bolt, as shown in Figs. 5 and 11. This spring normally retains the firing pin slide in a rearward position in the breech bolt so that the firing pin 46 in its normal position will be held from contact with a cartridge when the breech bolt is in its forward position.

A spring supporting rod 50 extends into a bore 25 in the rear end of the breech bolt and has a head 51 seated against the bottom of said bore and against a shoulder 52 on the firing pin slide, a notch 53 extending inwardly from said shoulder as shown in Fig. 4. A breech bolt closing spring 30 54 is supported by the rod 50 and thrusts with its rear end against the bottom of a recess 55 in the screw plug 39.

A hammer 56 is slidably mounted for reciprocating movement in the receiver and is urged 35 forward for firing operation by a hammer spring 57 supported on a sleeve extension 58 from the screw plug 39, said spring thrusting at its rearward end against the end of the plug at the base of said sleeve and at its opposite end against the 40 bottom of a hole in the hammer into which the spring extends.

The hammer has a sear engaging notch 59 which in fact is a shoulder extending around the hammer to receive the pointed end of a sear 60 45 pivotally mounted in a screw threaded stud 61 secured in the receiver. The sear is biased into engagement with the hammer by a sear spring 62, as shown in Fig. 4. Said hammer has also a disconnector 63 in the form of an enlargement 50 on the hammer to retain the sear in a disconnected position to be hereinafter described. A trigger 64 is pivotally mounted in a trigger supporting stud 65 secured in the under side of the receiver, said trigger being curved as at 66 around 55 the magazine 21, as shown in Fig. 10 of the drawings. A trigger spring 67 urges the trigger forward. A connector 68 is pivotally supported at one end by the trigger and its opposite pointed end is spring biased into engagement with a 60 notch in the sear 60 as shown in Fig. 4, whereby backward pull upon the trigger 64 will effect disengagement of the sear from the hammer permitting the latter to be forced forward by its spring into forcible contact with the projecting 65 back end of the firing pin slide 45 shown in Fig. 4 of the drawings.

This slide 45 has a cartridge releasing notch 69 in its bottom edge to receive the cartridge retainer 35, as shown in Fig. 4, for the purpose 70 of releasing the cartridges to permit their forward movement in the magazine tube under the impulse of the spring 30. A cocking handle 71 having a cocking pin 72 is insertable through a slot in the side of the receiver and in the breech 75 bolt 40 and firing pin slide 45, as shown in Figs.

5 and 12 of the drawings, this handle being yieldingly and removably held in place by a spring pressed plunger 73 as shown in dotted lines in Fig. 5 of the drawings.

In the operation of the firearm, assuming that 5 the gun is unloaded and the parts are all in their normal positions of rest, the magazine tube 21 is removed by grasping the fingerpiece 28 and releasing it from the bayonet lock, whereupon the tube is pulled out from the breech thereby leaving the loading case 22 open and free to receive cartridges to its capacity, or to such extent as may be desired. The magazine tube is now inserted into the loading tube and pushed inwardly to its full extent and locked in place. During 15 this inward movement of the tube 21 the cartridges will successively be entered into the front end of the tube until the latter is locked in position whereupon the spring 30 will exert its force forwardly on the line of cartridges, the leading 20 cartridge being in contact with the under surface of the breech bolt.

The cocking handle 70 may now be inserted into the breech bolt as shown in Fig. 12 and used to slide the breech bolt backwardly to cock the 25 hammer, the breech bolt then being moved forwardly aided by the spring 54 into the position shown in Figure 4. During this forward movement of the breech bolt the firing pin slide will be held in its rearward position in the breech bolt 30 so that it will not come in contact with any cartridge that may be in firing position in the breech of the barrel.

As the breech bolt is moved forwardly the hammer will be held in its backward or firing 35 position by the sear 60. The gun is now in condition for firing and backward pull upon the trigger 64 will actuate the connector 68 to force the sear 60 from engagement with the hammer, and the latter will then be forced forwardly under 40 the force of the hammer spring 57, striking the projecting rear end of the firing pin slide 45 and forcing the firing pin 46 against the cartridge thereby exploding the same. Under the forces of explosion the breech bolt will be blown back carrying with it the hammer which will be retained in its firing position by the sear 60, and the breech bolt will be forced forward by the spring 54 into firing position, the firing pin being prevented from contact with the cartridge in the 50 breech of the barrel as hereinbefore described. As the breech bolt is moved back as just described, an extractor 73 will extract the cartridge shell from the breech of the barrel and move it into contact with an ejector 74 whereby the shell 55 will be ejected through an opening 75 in the receiver in a well known manner.

During this rearward movement of the breech bolt carrying with it the firing pin slide the leading cartridge in the magazine tube and underlying 60 the breech bolt will be uncovered and the pressure of the spring 30 will force the line of cartridges forward, the forward cartridge nosing up an incline 76 at the front end of the tube and into contact with the guide lug 43 which will 65 guide it into the breech in the barrel. The force of the spring 30 will be such that the cartridge is thrown into the chamber in the rear end of the barrel as illustrated in Fig. 5. As the firing pin slide 45 moves backwardly the sloping rear end 70 of the notch 69 will press the forward end of the cartridge retainer downwardly so that the fork thereon will be in line with the rim of the cartridge shell, and as the line of cartridges are moved forward this fork engaging said rim will 75

hold the cartridges in the position shown in Fig. 5. As the breech bolt and firing pin slide move forwardly as hereinbefore described the leading cartridge in the magazine will be pressed downwardly into the position shown in Fig. 4.

In the operation of firearms of this type there is liability, unless means are provided to prevent it, that the pressure of the finger upon the trigger 64 will not be released quickly enough to enable the sear 60 to get into position to engage the hammer as it is forced back and prevent immediate forward movement thereof. This would result in a second and unintentional firing of the gun. To obviate this I have provided the disconnector 63 on the hammer which, as the hammer moves forward in the firing operation, engages the sear and forces it downward against the connector into the position shown in Fig. 7 so that the point of the connector is below and forward of the shoulder of the notch in the sear. If the pressure upon the trigger is prolonged, as just referred to, the point of the connector 68 will be retained during such pressure in this position, leaving the sear free to be forced upwardly by its spring into position to engage the hammer when it is forced backwardly by the movement of the breech bolt as hereinbefore described. After this operation and when pressure on the trigger is released the parts will resume the position shown in Fig. 4 ready for another firing operation.

An important feature of the invention resides in an elevator for raising the rear end of the cartridges out of the pocket created by the incline 76 so that the axis of the cartridge will be substantially in line with the axis of the bore of the barrel. This elevator comprises shoulders 77 created by cutting slits in opposite sides of the tip and forcing said sides inwardly as shown in Fig. 9. In the loading operation when the cartridge is forced from the pocket and from the position shown in Fig. 4, the rim of the cartridge shell engaging the elevating shoulders 77 is raised so that its axis is in line with the axis of the bore of the barrel and permits the cartridge to readily enter said bore and into the position shown in Fig. 5. When the breech bolt closes, after the firing operation, its forward end striking the cartridge will force it into the barrel into the position shown in Fig. 4, the firing pin during this operation and as hereinbefore explained being held in its rearward position by the spring 48 so that the pin will not strike the cartridge when the breech bolt closes.

The nut 23 engaged with the screw threaded part of the case 22 permits endwise adjustment

of the case to compensate for slight variations in construction and also to properly position the forward end of the magazine for proper functioning of the loading and extracting mechanism, and the yielding feature provided by the spring 5 25 is for the same purpose.

The trigger 64 has a slot cut into its upper end to receive the end of the connector 68, the pivot for the connector passing across the slot in a manner well known in structures of this type. 10

I claim:

1. A firearm including a stock, a receiver mounted in the stock and having an opening therein, a barrel secured to the receiver, a hammer slidably mounted in said opening and having 15 a sear notch, a sear in the form of a lever pivotally supported by the receiver and extending lengthwise thereunder, a trigger pivotally supported by the receiver, a connector in the form of a lever pivotally supported at one end by the trigger and extending under the sear for engagement with a sear notch in the latter, and a formation on the hammer to contact the sear and retain it from engagement with the connector after disengagement of the latter from the sear. 25

2. A firearm including a stock, a receiver mounted in the stock and having an opening therein, a barrel secured to the receiver, a hammer slidably mounted in said opening and having 30 a sear notch, a sear in the form of a lever pivotally supported by the receiver and extending lengthwise thereunder, a trigger pivotally supported by the receiver, a connector in the form of a lever pivotally supported at one end by the trigger and extending forwardly underneath the 35 sear for engagement with a sear notch in the latter, and a formation on the hammer to contact the sear to impart added movement thereto after its disengagement from the connector.

3. A firearm including a stock, a receiver 40 mounted in the stock and having an opening therein, a barrel secured to the receiver, a hammer slidably mounted in said opening and having a sear notch, a sear in the form of a lever pivotally supported by the receiver and extending 45 rearwardly lengthwise thereunder, a trigger pivotally supported by the receiver, a connector in the form of a lever pivotally supported at one end by the trigger and projecting forwardly under the sear for engagement with a sear notch there- 50 in, and a formation on the hammer to contact the sear and force it into engagement with the connector to disengage the latter from said sear notch.

EUGENE G. REISING. 55
